[57] CLAIM

The ornamental design for a data-collection apparatus, as shown and described.

DESCRIPTION

FIG. 1 is a left front perspective view of a data-collection apparatus showing our new design; and FIG. 2 is a right rear perspective view of said apparatus. The recess in the bottom panel, shown near the lower left corner of FIG. 2, is rectangular in shape and extends toward the front panel a distance of four times the height of the adjoining recess in the rear panel.

FIG. 1
